UNITED STATES PATENT OFFICE.

HERBERT H. STEELE, OF MARCELLUS, NEW YORK, ASSIGNOR TO THE MONARCH TYPE-WRITER COMPANY, OF SYRACUSE, NEW YORK, A CORPORATION OF NEW YORK.

TYPE-WRITING MACHINE.

1,032,090.

Specification of Letters Patent.

Patented July 9, 1912.

Application filed May 9, 1911. Serial No. 625,957.

To all whom it may concern:

Be it known that I, HERBERT H. STEELE, citizen of the United States, and resident of Marcellus, in the county of Onondaga and 5 State of New York, have invented certain new and useful Improvements in Type-Writing Machines, of which the following is a specification.

My invention relates to typewriting machines and more particularly to the carriage escapement mechanism.

The principal object of my invention is to provide a simple and efficient escapement for the carriage of a typewriting machine 15 and one that can be readily converted to give either a reverse or an ordinary feed.

To the above ends my invention consists in certain features of construction and combinations and arrangements of parts, all of 20 which will be fully set forth herein and particularly pointed out in the claims.

In the accompanying drawings, which are on an enlarged scale, Figure 1 is a side elevation of the escapement mechanism of a 25 Monarch typewriter having my invention embodied therein and with some of the parts shown in vertical section. Fig. 2 is a rear elevation of the escapement mechanism with parts in section and parts broken away. 30 Fig. 3 is an isometric view of one of the feed dogs. Fig. 4 is a top plan view of the upper end of the dog rocker with certain parts of the two dogs shown in section. Fig. 5 is a 35 view of the two dogs and the upper end of the dog rocker in fore and aft vertical section and looking toward the right, this view being on a larger scale than the others. Figs. 6, 7 and 8 are diagrammatic plan views showing the two dogs and two teeth of the 40 escapement rack with the parts in different positions in the different views, and illustrating the action of the escapement when set for reverse feed. Figs. 9, 10 and 11 are 45 views of the same sort as Figs. 6, 7 and 8 but illustrating the action of the escapement when set for ordinary feed.

My invention is applicable or capable of being adapted to various styles of typewriting machines but it is here illustrated in 50 connection with the Monarch typewriter. The main frame of the Monarch machine comprises a top plate 1 from which rise standards 2 which support stationary grooved rails 3 which guide anti-friction 55 balls or rollers 4 which in turn support a

carriage 5. Said carriage is drawn toward the left by the usual spring drum (not shown) and its letter-feed motion is controlled by means comprising a feed rack 6 which is mounted on arms 7 which are pivoted at 8 to the end pieces of the carriage. Said feed rack engages a feed pinion 10 on the forward end of a shaft 11 journaled in a bracket 12. At its rear end said shaft has loosely mounted thereon an escapement 65 wheel 13 and also, rigidly mounted thereon, a barrel 14 containing the usual pawl and ratchet connection between the escapement wheel and the shaft. The parts thus far described are here shown as of the ordinary 70 Monarch construction but as far as my invention is concerned they may be of any suitable construction. The Monarch machine also has a bracket 15 depending from the top plate and in which is pivoted the 75 axle or cross shaft 16 of a dog rocker having an upwardly extending arm 17 and a forwardly extending arm 18, the last connected by a link 20 with the universal bar of the machine. The dog rocker is held in its normal position by a spring 21 and its motion under the impulse of said spring is limited by a stop screw 22 and the motion of the dog rocker under the operation of the link 20 is limited by a second stop screw 23, all of 80 these parts being substantially as heretofore constructed.

I construct the upper end of the arm 17 of the dog rocker with a somewhat enlarged head 24 which, as here shown, is flat on top 90 except that it is formed with two horizontal grooves 25 and 26 extending crosswise of the machine, as best shown in Figs. 4 and 5. These grooves are guide grooves for a pair of slides 27 and 28 having projecting upward therefrom teeth 30, 31, said teeth and slides constituting the feed dogs that control the teeth of the wheel 13. In order to retain the slides in place in their grooves, each of said slides is formed in one of its 100 vertical faces with a longitudinal slot 33 and a hole is drilled in from one face of the head 24 and through the tongue or partition 34 that separates the two grooves 25 and 26. A pin 35 is forced through the hole in the 105 partition 34 so that its forward end projects into the groove 33 in the slide 27, as shown in Fig. 5, this pin having a tight fit in the head of the dog rocker. Another pin is provided for the rear slide 28 but the latter pin 110

is here shown as the reduced inner end of a screw 36 threaded into the hole referred to.

In order to limit the sliding motion of the slides 27 and 28 in one direction, each of said slides is formed with a depending finger 37 adapted to strike against the right-hand face of the head 24 of the dog rocker. In order to limit the motion of the slides in the opposite direction, each of them is formed at its opposite end with a second depending arm 38, which last is shown in section in Fig. 4. These arms 38 play in vertical slots 40 and 41 cut in the head 24 of the dog rocker, as best shown in Fig. 4, in which figure it will be noted that the rear slot 41 is cut deeper by a certain amount into the head of the dog rocker than the forward slot 40 and also that the arm 38 of the rear slide is thicker by the same amount in a right and left-hand direction than the corresponding arm of the forward slide. The slides 27 and 28 are impelled toward the left, that is to say, against the direction of motion of the lower part of the escapement wheel, by springs 42 seated in suitable bores 43 in the dog rocker and each at its left-hand end surrounding a pin 44 projecting toward the right from the arm 38.

In order to convert the escapement from reverse to ordinary or vice versa, I provide means for holding one or the other of the slides in a right-hand position against the tension of its spring 42. A switch, here shown as consisting of a plate 45 of sheet metal, is pivoted to the arm 17 of the dog rocker against the flat left-hand face of said arm on a shouldered and headed screw 46. Said plate is formed with a concentric slot 47 through which passes a headed screw 48, said slot serving to limit the motion of the plate about its pivot and said screw when tightened serving also to hold the plate in either of its two positions. The upper end of the plate 45 has a finger 49 bent off horizontally therefrom, as shown, and serving when the plate is in the position shown in Fig. 1, to limit the right-hand motion of the rear slide 28, and when said plate is set or adjusted to its rear position, this finger 49 is out of the path of the dogs and inoperative. The forward upper part of the plate 45 is formed with a holding device consisting, as here shown, of a second finger 50, which occupies the position shown in Fig. 5 and is bent as shown in Fig. 2; that is to say, this finger is in front of the finger 49 and it is bent off first toward the left and thence upward, said finger 50 being adapted when the plate 45 is in its forward position, as shown, to engage to the left of the arm 38 of the forward slide 27 and to hold said slide in its extreme right-hand position, as shown in Figs. 2 and 4. When the plate 45 is set to its rear position, this finger 50 is adapted to engage the arm 38 of the rear

slide 28 and to hold said rear slide in its extreme right-hand position, leaving the forward slide free to move back and forth across the head of the dog rocker. One or both of the edges of the finger 50 are rounded as shown at 51 to wedge the arm 38 toward the right.

The escapement is shown in the drawings set for reverse feed, this being accomplished by setting the plate 45 to its forward position and securing it there by tightening the screw 48. It will be noted that when the parts are in this position the finger 49 stops the arm 38 of the rear slide 28 before said arm reaches the bottom of the slot 41. The result is that when a key is depressed and the rear dog 28-31 engages the wheel, said dog is arrested before the face thereof is quite even with the face of the forward dog 30. In other words, a slight drop is provided between the dog 31 and the dog 30. Fig. 6 shows diagrammatically the normal position of the parts when the escapement is set for reverse feed. In this and the other diagrammatic views one of the teeth of the escapement wheel is marked *a* and the next succeeding one is marked *b*. It will be noted that the tooth *a* is in engagement with the dog 30 in Fig. 6. When the key is depressed the parts move to the position shown in Fig. 7 where the tooth *b* has engaged the dog 31 and forced it as far to the right, or to the left as viewed in said figure, as it will go. When the key is released the parts move to the position shown in Fig. 8 with the tooth *b* held by the dog 30.

In order to obtain an ordinary feed, the screw 48 is loosened and the plate 45 is set to its rear position, first pressing the slide 28 to the right so that it will be held in its right-hand position by the finger 50. When this is done the finger 49 moves out of the way of said arm 38 and the finger 50 holds said arm in the extreme bottom of the slot 41 so that the parts normally stand in the position shown in Fig. 9 where it will be seen that the dog 30 has a slight lead over the dog 31. It will be perceived that the stop finger 49 serves to reverse the lead when the plate 45 is adjusted from one of its positions to the other. When the key is depressed the parts move to the position shown in Fig. 10 where the tooth *a* of the escapement wheel is held by the dog 31, said tooth having been permitted to move only the very slight distance provided for by the drop between the two dogs. The dog 30 has been moved toward the left by its spring 42. When the key is released the dog 31 moves out of the path of the tooth *a*, the dog 30 moves into the path of the tooth *b*, and the wheel and carriage make their step and force the dog 30 back to its normal position where it holds the tooth *b* as shown in Fig. 11.

It will be noted that the mechanism is

very simple and that the device for changing from one style of feed to the other is extremely simple.

A single dog, similar to one of the dogs here shown and mounted on the dog rocker in a similar way, is shown and claimed in my prior pending application filed October 24th, 1910, Serial No. 588,682.

Various changes can be made in the details of construction and arrangement of the parts without departing from my invention.

What I claim as new and desire to secure by Letters Patent, is:—

1. In a typewriting machine and in escapement mechanism, the combination of an escapement rack, a dog rocker, two dogs mounted to slide horizontally on said dog rocker and having parallel depending arms, springs for sliding said dogs against the direction of motion of said rack, and a switch having a holding device engageable with said arms alternatively to hold the dog whose arm is engaged against the tension of its spring.
2. In a typewriting machine and in escapement mechanism, the combination of an escapement rack, a dog rocker, two dogs mounted to slide on said dog rocker and each having an arm, springs for sliding said dogs against the direction of motion of said rack, and a switch having a holding device engageable with said arms alternatively to hold the dog whose arm is engaged against the tension of its spring, and said switch having also a stop to reverse the lead between said dogs.
3. In a typewriting machine and in escapement mechanism, the combination of an escapement rack, a dog rocker two dogs mounted to slide on said dog rocker and each having an arm, springs for sliding said dogs against the direction of motion of said rack, and a switch pivotally mounted on said dog rocker and having two fingers, one arranged to engage one face of one of said arms in one adjustment of said switch and the corresponding face of the other of said arms in another adjustment of said switch to hold the dog whose

arm is engaged against the tension of its spring, and said switch having also a stop which, in one adjustment of said switch, engages behind the arm of one of said dogs to reverse the lead between the dogs.

4. In a typewriting machine and in escapement mechanism, the combination with an escapement rack, of a dog rocker having two transverse grooves therein and a hole extending through one outer wall into one of said grooves and a registering hole through the partition between said grooves, two sliding dogs mounted in said grooves and each having a slot lengthwise thereof, and pins in said holes engaging in said slots to retain said dogs in said grooves.

5. In a typewriting machine and in escapement mechanism, the combination of an escapement rack, a dog rocker, two dogs mounted on said dog rocker for motion relative to said dog rocker and each of said dogs having an arm and one of said arms being thicker by a certain amount than the other, two parts on said dog rocker against which said arms abut to limit the motion of said dogs in one direction, one of said parts being deeper than the other by an amount corresponding to the difference in the thickness of said arms, springs for moving said dogs against the direction of motion of said rack, a holding device mounted on said dog rocker and adjustable to engage said arms alternatively on the sides of said arms opposite those which abut said parts of said dog rocker to hold the dog whose arm is engaged against the tension of its spring, and a stop adjustable to arrest one of said arms before it reaches its abutting part of the dog rocker when said holding device is adjusted to engage the other arm.

Signed at Syracuse, in the county of Onondaga, and State of New York, this 5th day of May, A. D. 1911.

HERBERT H. STEELE.
